COMBINED CONTAINER AND DISPENSER FOR POWDERED MATERIALS

Jean Emery, 132 Rue Perronet, Neuilly-sur-Seine, France

Filed Jan. 14, 1971, Ser. No. 106,636

Term of patent 3½ years

Int. Cl. D9—07

U.S. Cl. D9—207

FIG.1

FIG.2.

FIG. 1 is a top, front and right side perspective view of a combined container and dispenser for powdered materials showing my new design; and

FIG. 2 is a rear elevation view thereof, the left side being identical to the right side and the bottom being substantially unornamented.

I claim:

The ornamental design for a combined container and dispenser for powdered materials, as shown and described.
